UNITED STATES PATENT OFFICE

FRANK DUTCHER, OF ROGERS, OHIO

RAILWAY SIGNAL TORPEDO

Application filed May 8, 1931. Serial No. 536,057.

This invention relates to certain improvements in railway signal torpedoes and it has certain objects in view which will be set forth hereinafter.

5 As is well known to those skilled in this art railway signal torpedoes are attached to the head of railroad rails to be exploded by the passing wheel of a locomotive.

The present invention relates to the following improvements whereby a torpedo is produced which is cheap to produce and is simple in construction.

10 In carrying out the present invention the explosive compound is preferably in tablet form and it is enclosed in a casing that is wrapped therearound having extended ends, and applying to this explosive compound a plate that is located between the extended ends and the body portion of the torpedo and 15 to place said ends under a constant closing pressure whereby the casing is made waterproof without the use of cement.

The records of the patents granted on railway signal torpedoes establish that I have 20 been engaged in the manufacture of them for a great many years and so far as I am aware heretofore torpedoes of the type herein described have not had the extended ends of the case united to the torpedo by means 25 of a plate applied thereto, in the manner hereinafter described.

30 My present improvement is to use the plate as means around which these extended ends are tightly wrapped and placed under closing tension thereby keeping moisture and water 35 from contact with the explosive contained therein, and further more the present invention is in utilizing a spring member for holding the torpedo to a rail as further means for 40 exerting a closing pressure on the extended ends of the torpedo case.

Another object of the invention is in the particular construction of the plate and the spring holding member as hereinafter shown 45 and described.

A further object of the present improvement is to place the extended ends of the explosive containing case between the unyielding surface of a plate applied to the under- 50 side of the torpedo case and in utilizing the

unyielding closing tension of a spring holding member, which I believe to be new in torpedoes.

In the accompanying drawings:

Figure 1 is a perspective view of a torpedo embodying my present improvement.

Fig. 2 is an inverted perspective view of Figure 1.

Fig. 3 is a cross sectional view taken centrally through the torpedo.

Fig. 4 is a side view showing the spring member made in two parts.

Fig. 5 is a side view of the assembled torpedo.

In carrying out my present improvement I utilize an explosive tablet 1 that is wrapped in a casing 2 with the ends 3 of the wrapped casing extended. These extended ends are substantially about half as long as the width of the casing. Applied to the under side of the casing 2 is a plate 4 and the ends 3 are tightly wrapped around this plate and are held in this tightly wrapped position by means of a spring clip 5 that also serves to unite the torpedo to the head of a railroad rail. The wrapping tightly of these ends 3 around the plate 4 serves to put a closing tension on these ends at the points where they are doubled around the plate, and the holding clip member 5 also serves to put a closing tension on the ends 3 that lie between the spring member 5 and the said plate. Preferably the spring member 5 is united to the ends 6 of the said plate by means of suitable rivets 7.

The spring member 5 is shaped substantially like the spring holding member in my application Serial No. 536,056 filed May 8, 1931, and hence any special description of this member is unnecessary in connection with this present improvement. The ends 8 may be made in the form here shown and these ends 8 may interlock with a raised portion 9 of the holding member 5 or may interlock with the ends 10 (Figure 4) as may be preferred. The object of having these ends interlock as here shown is to economize space in shipping torpedoes provided with spring members that unite the torpedo to the head of a railroad rail. This closing and holding fea-

ture is no part of the present invention since that is described in my above referred to pending application.

For the purpose of holding the casing 5 against longitudinal movement on the plate 4, said plate is cut out longitudinally to form shoulders 12 which abut against the ends of the casing. This serves to prevent any end- 10 wise movement of the casing in respect to the plate.

So far as I am aware heretofore the ends 3 of casings have not been clamped between a plate and a rail engaging member whereby there is a double closing action on the ends of 15 the casing, viz, where these ends are doubled around the plate and having the metal rail engaging member clamping the said ends against the said plate.

This torpedo has the advantages that are 20 defined in my above referred to pending application so far as the metal strips that the holding member consists of is concerned and so far as the saving in space and in freight is concerned.

25 Railway signal torpedoes it is well known have to meet severe conditions, that is they have to stand severe weather in use and they must always be reliable because lives and property are at stake. Therefore any improvement that adds certainty to a railway torpedo is considered of major importance. Railway signal torpedoes are manufactured and sold at a price approximately two cents each and therefore the cost of production is 30 important.

It will be observed that the extended ends 3 are placed under a closing tension between a nonyielding plate 4 and a nonyielding clip member 5 for holding the torpedo on the head 40 of a railroad rail.

The casing 2 consists of course of water- 45 proofed material as heretofore, but heretofore it has been necessary to utilize cement to close the ends of this wrapping and one idea 50 of the present improvement is to avoid this expense which I do by subjecting these extended ends to the double closing pressure herein referred to and the cost is reduced because of the use of a metal for the torpedo 55 holding device that does not require to be formed up and afterwards tempered etc. and by making a construction that is simple to produce and that is simple to assemble by not requiring any special machinery to accomplish either purpose.

The present invention has been particularly 60 described but I wish it understood that it may be varied in certain respects without departing from the spirit and scope of the invention so long as those changes come within 65 in a liberal interpretation of the appended claims.

Having thus described my invention what 70 I claim and desire to secure by Letters Patent is:—

1. An improved torpedo consisting of an explosive wrapped in a casing having extended ends, a plate applied directly to the underside of the casing with said extended ends bent around the edges of the plate, thereby putting a closing tension on them and, attaching to the said plate, a rail engaged member extending longitudinally of the said ends and placing on them a second closing tension substantially as set forth. 75

2. A torpedo comprising an explosive packed in a water-proofed wrapper having ends extending beyond the edges of the torpedo, a plate applied directly to the bottom of the said casing, said ends wrapped around the plate with their extremities lying outside of said plate, said plate having its ends extending beyond said casing and a rail engaging member attached to the extending ends of the plate, said plate exerting a second closing tension on the said casing ends, substantially as set forth. 80

3. A torpedo comprising an explosive wrapped in a sheet and when wrapped having extended ends, a plate applied directly to the bottom of the said torpedo, said plate being cut out a distance substantially the length of the said torpedo, the extended ends being doubled around in said cut out portion, the said plate and a rail engaging member connected with the said plate and exerting a second closing action on the said extended ends, substantially as set forth. 85

4. A torpedo comprising an explosive compound wrapped in a casing having extended ends, a plate applied directly to the underside of said casing, said plate having a non-yielding outer surface said plate provided with extended ends and a clip attached to said extended ends and applied to the outer sides of said extended ends, said clip having a non-yielding inner surface whereby a closing tension is exerted on said extended ends of the case. 100

In testimony whereof I hereunto affix my 105 signature.

FRANK DUTCHER.
